(57) **CLAIM**

The ornamental design for a photo frame, as shown and described.

DESCRIPTION

FIG. 1 is a front, left and top perspective view of a photo frame, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the photo frame that form no part of the claimed design.
